(57) **CLAIM**

The ornamental design for a reinforcement concrete hanger, as shown and described.

DESCRIPTION

FIG. 1 is a front facing view of the reinforcement concrete hanger in accordance with our new design, the rear facing view being a mirror image thereof;

FIG. 2 is a top plan view thereof;

FIG. 3 is a bottom view thereof; and,

FIG. 4 is a left side view thereof, the right side view being a mirror image thereof.
